Frank J. Baldwin

ATTORNEY.

UNITED STATES PATENT OFFICE

WILHELM WUNSCHE, OF DETROIT, MICHIGAN

BUCKLE

Application filed June 2, 1932. Serial No. 614,927.

This invention relates to improvements in buckles or strap coupling members, and aims to provide a type of buckle to which the adjacent ends of two straps may be secured in such a manner that either strap may be secured to said buckle at varying distances from its extremity without disturbing the setting of the other strap.

It is an object of the invention to provide a buckle which may be readily employed to adjust the overall length of two straps as there are many purposes for which such ready adjustment is required, as for instance in the case of the hobble shown and described in my United States Patent No. 1,782,835 issued on November 25th, 1930, in which a different form of coupling member or buckle was shown for accomplishing this purpose.

Another object of the invention is to provide such a buckle or strap coupling member which is cheap and simple to manufacture, and with the aid of which adjustment of the overall length of two straps may be readily made.

With these and other objects and advantages in view which will become apparent as the specification proceeds, the invention is hereinafter more fully described with the aid of the accompanying drawing, in which:

30 Figure 1 illustrates a plan view of the invention, and

Figure 2 is a side view thereof.

Figure 3 shows a plan view of a slightly modified construction, and

35 Figure 4 is a side view of Figure 3.

Referring to the drawing, 1 designates a base having opposed upwardly projecting sides 2 and 3 formed thereon adjacent its extremities. The sides 2 are connected at their upper ends by an integral top portion 4 thereby forming a tubular guide for the passage of a strap 5. Integral with the upwardly projecting sides 3 are lugs 6 having openings therethrough for a hinge pin 7 on

40 which one extremity of a plate 8 is pivotally mounted. Through the guides formed between the sides 3 and beneath the pivoted end of the plate 8 a second strap 15 extends.

45 The other extremity of the plate 8 is adapted to rest on the upper faces of the sides 2

adjacent the top portion 4, and 9 denotes a catch pivoted on the said top portion which is adapted to extend over the outer extremity of the plate 8 and retain it in the closed position shown.

Extending upwardly from the base 1 are prongs 10 for the passage of which suitable apertures 12 are formed through the plate 8. Through the straps 5 and 15 openings 5a and 15a are provided to engage the said prongs.

Figures 1 and 2 show apertures 16 and 17 formed through the plate 8 and base 1 respectively intermediately of their length for the passage of the free ends of the straps 5 and 15, whereas in the construction shown in Figures 3 and 4 these apertures are omitted and the free ends of the said straps are flexed laterally so that they project outwardly on opposite sides of the buckle.

From the foregoing it will be readily seen that when the plate 8 is turned to an inclined position about the hinge pin 7, the straps 5 and 15, or either of them, may be readily set so that each prong 10 engages any desired opening 5a or 15a in the strap 5 or 15 which it engages. Thus the distance from the outer extremity of either of both of the straps 5 and 15 to the buckle may be readily varied.

While the preferred embodiments of the invention have been described and shown, it is understood that the construction is susceptible to such further alterations and modifications as fall within the scope of the appended claims.

What I claim is:

1. A buckle comprising a flat base having opposed sides adjacent its extremities, a top portion connecting the upper ends of said sides at one extremity of the base, thereby forming a tubular guide, a plate pivotally supported between the sides at the other extremity of the base and spaced above the latter, means adapted to hold the outer extremity of the plate on the upper ends of the sides adjacent said top portion, the pivoted extremity of the plate and the base sides on which it is pivoted forming a second tubular guide, prongs extending upwardly from said base, a strap having spaced openings therethrough extending through each tubu-

lar guide, any one of said openings in one strap being adapted to be engaged by one prong, and any one of the openings in the other strap being adapted to be engaged by
5 the other prong.

2. A buckle comprising a flat base having opposed sides adjacent its extremities, a top portion connecting the upper ends of said sides at one extremity of the base, thereby
10 forming a tubular guide, a plate pivoted between the sides at the other extremity of the base and spaced above the latter, means on said top portion adapted to hold the outer extremity of the plate on the upper faces of
15 the sides adjacent said top portion, the pivoted extremity of the plate and the base sides on which it is pivoted forming a second tubular guide, prongs extending upwardly from said base and through openings formed in
20 said plate, a strap having openings therethrough extending through each tubular guide, any one of the openings in one strap being adapted to be engaged by one prong between said base and said plate, and any
25 one of the openings in the other strap being adapted to be engaged by the other prong between said base and said plate.

3. A buckle comprising a flat base having opposed sides adjacent its extremities, a top portion connecting the upper portions of said sides at one extremity of the base thereby forming a tubular guide, a plate pivotally supported between said sides at the opposite extremity of the base and spaced above the latter, said latter sides and plate forming a second tubular guide, the outer extremity of said plate being adapted to rest on the top of said sides at the first mentioned end of the base adjacent said top portion, means adapted
35 to hold the outer end of said plate relative to said top portion, prongs extending upwardly from said base, the base and said plate being apertured intermediately of its length, and a strap having spaced openings therethrough extending through each tubular guide, any one of the openings in one strap being adapted to be engaged by one prong, and any one of the openings in the other strap being adapted to be engaged by the other prong, the free end of one strap extending
40 through the base opening and the free end of the other strap extending through the plate opening.
